(57) **CLAIM**

I claim the ornamental design for a lower garment with a beverage theme, as shown and described.

DESCRIPTION

FIG. 1 is a rear perspective view of a lower garment with a beverage theme, showing my new design;
FIG. 2 is a front elevational view thereof;
FIG. 3 is a rear elevational view thereof;
FIG. 4 is a right-side elevational view thereof;
FIG. 5 is a left-side elevational view thereof;
FIG. 6 is a top plan view thereof; and,
FIG. 7 is a bottom plan view thereof.

The broken lines showing a leg portion of the garment in the figures depict environmental matter and form no part of the claimed design.
